UNITED STATES PATENT OFFICE.

JOHN F. MAGLONE, OF PROVIDENCE, RHODE ISLAND.

NECK SCARF OR TIE.

1,007,465.

Specification of Letters Patent. Patented Oct. 31, 1911.

Application filed October 12, 1910. Serial No. 586,713.

To all whom it may concern:

Be it known that I, JOHN F. MAGLONE, a citizen of the United States, residing at the city of Providence, in the county of Providence and State of Rhode Island, have invented certain new and useful Improvements in Neck Scarfs or Ties, of which the following is a specification, reference being had therein to the accompanying drawing.

10 This invention has reference to neck scarfs or ties, its object being to provide a tie having that portion which passes around the neck, or between the folds of a turn-down collar, made of a separate material 15 from that of which the exposed ends are constructed, said center portion being made of a very thin yet strong material to prevent binding beneath the collar and to admit of ready adjustment without undue 20 pulling or straining the tie.

A further object of the invention is to provide a scarf of this character which is less expensive to manufacture as much shorter length of the silk, or other material 25 of which the end portions are constructed, may be used, both the wide end, and narrow center sections being cut separate and independent, thus enabling them to be cut from the piece to the best advantage and with the 30 minimum amount of waste.

With these and other objects in view, the invention consists of certain novel features of construction, as will be more fully described and particularly pointed out in the 35 appended claim.

In the accompanying drawings: Figure 1—is a side elevation of my improved tie showing a portion of the center member broken away. Fig. 2—is an enlarged perspective view illustrating one method of 40 constructing the ends of the middle portion into which the ends of the tie are set and fastened. Fig. 3—is a section on line 3—3 of Fig. 2.

45 Referring to the drawings, 1 designates the middle section of the tie which is preferably constructed of very thin, light yet firm and strong material, such as linen, mohair, or other suitable material, the ends 2—2 of which section are preferably formed double, said doubled portions being open at their extremities 3, each also open at one edge 4, for a short distance as illustrated in Fig. 2, said doubled and split end being for the purpose of receiving one end 5, of the end portion 6 which may be inserted therein and

secured by sewing, or other suitable means. These tie end portions are of course comparatively short and may be constructed of silk, or other suitable material, which may be of a more expensive quality than that of which the middle section is constructed, as of course these ends are the only portions exposed to view when the tie is in position around the neck of the wearer.

I do not wish to be restricted to forming the center section of material having but a single thickness as the same may be constructed of tubular material, if desired, and the tie ends fastened into each end of the tube.

The usual high grade silk tie is made of one piece of material and lined or padded, particularly in that portion which passes around the neck, for the purpose of reinforcing or strengthening the silk and giving shape to the tie. This padding has a tendency to make the tie thick, heavy, and clumsy under the collar causing the same to bind particularly when passing between the folds of a turn-down collar, and to prevent adjustment of the tie without considerable pulling and consequent straining of the tie which shortens its life and soon destroys it. By my improved construction I reduce the thickness of that section which passes beneath the collar by making it preferably of a single thickness of very strong material thereby materially reducing the friction of moving or sliding it back and forth between the folds of the collar.

Another feature of my invention, particularly from a manufacturer's standpoint, is the forming of the center section of the tie with open ends, as illustrated in Fig. 2, for the reception of the ends of the end portions of the tie, whereby the joint between the two sections is rendered practically invisible, the neat appearance of the tie preserved, and the expense of joining the parts together by sewing or otherwise reduced to the minimum.

Among other advantages in a neck scarf of my improved construction over the ordinary scarf is first, that the center section is thinner, will retain its shape longer, is much stronger and more durable than that of the ordinary tie; second, the tie may be more easily applied to the collar and readily adjusted without straining or injuring the tie; third, the tie is less expensive to manufacture, and fourth as the colors of the center

section may be made to match those of the ends the tie may be made as handsome and attractive in appearance as a tie of any other construction.

I claim:

A neck scarf comprising a thin flat middle section constructed of a firm tightly woven material of single thickness and provided at its ends with integral portions separated at their extremities and along one longitudinal edge, the end portions of said scarf being made of different material from

that of the middle section and secured between the separated end portions of the said middle section, said middle section being 15 substantially the width of the adjoining ends of the tying end portions.

In testimony whereof I affix my signature in presence of two witnesses.

JOHN F. MAGLONE.
